EXTENSION KEY CHAIN

Nathaniel N. Okun, Bronx, N. Y.

Application May 5, 1939, Serial No. 272,030

2 Claims. (CL. 24-3)

This invention relates to a key chain of a different arrangement than that shown in my co-pending application, now Patent No. 2,159,223, dated May 23, 1939, and has for one of its objects to provide a key chain, the effective length of which may be extended.

Another object of the invention is to provide a key chain which will enable proper length to be had whether it be worn by a tall person or a short person.

Another object of the invention is to provide a key chain having two or more sections which will extend one along the other and will permit a relative adjustment to change the effective length of the key chain.

Another object of the invention is to provide a key chain having means for providing a simple manner for adjusting the length such as by pulling with a suitable force upon one length of the key chain and suitably holding another part thereof.

Another object of the invention is to provide two separate sections of the key chain to take up the length thereof and an adjustment of those sections for varying the effective length of the chain.

Another object of the invention is to provide two units, each of which will be fixed to one section of a key chain while it is slideable along another section of the key chain.

A further object of the invention is to provide in such a unit an arrangement whereby the sliding action may occur without scratching or abrading the chain.

With these and other objects in view, the invention consists of certain novel features of construction, as will be more fully described, and particularly pointed out in the appended claims.

In the accompanying drawing:

Fig. 1 is an elevational view illustrating a key chain with the key holder and garment attaching means assembled therewith;

Fig. 2 is a sectional view of a greatly enlarged scale of the units whereby the adjustment of the flexible connection may be accomplished;

Fig. 3 is a sectional view of one unit showing the jaws in full and the parts in position to receive the cover plate;

Fig. 4 is a sectional view of the device complete; and

Fig. 5 is a perspective view illustrating the upper end portion of the device as connected in a different manner from that shown in Fig. 1 to a belt shown fragmentally.

In the use of key chains it frequently occurs

that the chain is either too long or too short, depending upon whether a tall or short person uses the same; also, it is often desirable to have a longer or shorter chain, depending upon different objects which are to be unlocked with the keys upon the key holder which is attached to the chain. For instance, some persons may care to have a chain sufficiently long to enable keys to be attached by the chain and still extend to the dash of an automobile for the ignition thereof and after such use to again shorten the chain; and in order that this may be provided, I have formed two sections of chain which extend one along the other and which may be relatively adjusted by reason of a friction member on the end of one which is permanently attached to the other whereby an effective adjustment of the length of the chain may be provided; and the following is a more detailed description of the present embodiment of this invention, illustrating the preferred means by which these advantageous results may be accomplished:

With reference to the drawing, I have illustrated an article holding element 10, here shown as a key ring or holder for keys, with a key 11 secured in position thereon. This element may be any desired shape or character for holding some sort of an article which is to be used in any of various ways. An element 12 is shown as of a type to attach to the garment of the wearer, such for instance, as to the edge of the trousers, through a belt loop or over the edge of the belt, and I have illustrated this element 12 as in the form of a clip having a spring jaw 13 of some desired form. The particular construction of this element, however, does not enter into the invention.

These elements 10 and 12 are connected together by some flexible connection which I designate generally 14 and which may consist of a chain, cord or similar forms of material. I have shown this flexible connection in this specific illustration as comprising two sections, one section being designated 15 and the other section 16, each section being in the form of a chain. These sections are arranged so that one will extend along or overlap the other, and I accomplish this by the use of two units designated generally 17 and 18.

These units are substantially identical and each is provided with friction jaws or glides 19 and 20, which glides are mounted within a casting 21. The glide 20 being fixed while the glide 19 is forced toward the glide 20 by a compression spring 22. A cover 23 serves to complete the

casing and hold the parts in their relative position. Openings 24 and 25 are provided through the unit for the reception of one of the flexible sections which as it passes through the unit has the pressure of the glides 19 and 20 upon it from opposite sides, the pressure being sufficient to hold the unit in an adjusted position on the flexible member when in normal untensioned condition, but which when sufficient pull is provided will cause the unit to slide along the section. The unit also provides some convenient means for the attachment of the end or end portion of one of the flexible members as at 28 to the unit, this being provided in the illustration here shown by means of an opening 27 smaller in one dimension than the link which it receives, one link being placed in edgewise through the slot in the unit while the next link will engage the edge of the slot to prevent escape therethrough, the end being held in position by the cover. Any convenient means of attachment may be provided, however.

The units are connected as shown more clearly in Fig. 2, by the end 28 of the chain section 15 being secured to the unit 17 and passing slidably through the channel provided in the unit 18 while the chain section 16 has its end 28 secured to the unit 18 and passes slidably through the unit 17 so as to be frictionally gripped thereby. With one end of the flexible member, such as that which is attached to the garment, anchored and the units in the relative position shown in Fig. 1, when a pull is exerted upon the key holder away from the anchored element 12, and this pull is sufficient, the unit 17 will be caused to slide along the section 16 and the unit 18 will likewise slide along the section 15 so that the units 17 and 18 will be brought closer together, their limit being when they are in contact and when such limit is reached the flexible connection between the elements 16 and 12 will be at its maximum length. If it is desired to contract the connection between the elements it is merely necessary to grasp each of the units 17 and 18 and move them in opposite directions, sufficient force being applied to cause the friction glides to slide along the sections in the opposite direction, the limit reached being that when the units engage either the element 18 or a portion connected to the element 12.

In some instances, it is not necessary to con-

nect the section 18 of the chain to some garment attaching element such as 12 as this chain may be looped around a belt 36 as shown in Fig. 5 with a clasp 38 to engage some link or eye 32 of the chain for holding it in position, or the chain may be passed through the opening 33 of the clasp, this illustrating a modified anchoring of this end of the flexible member of the device in position.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A device of the type described comprising a pair of flexible members having portions disposed in overlapping relation, a pair of units, one unit being relatively fixed to each member and containing within it friction-applying glides between which the other flexible member extends to be slidable therealong to dispose the members in varying amounts of overlapping relationship, an article holding element secured to one of said members beyond said overlapping portions and means also beyond said overlapping portions for securing the other flexible member to the wearing apparel.
2. A device of the type described comprising an article holding element, an element for attachment to a part of wearing apparel, a pair of flexible members, one connected to one of said elements and the other connected to the other of said elements, and extending one along another for a portion of their length when the device is in contracted position, a pair of units each containing within it friction applying glides, one unit being slidable along one member and connected the other member and the other unit being slidable along the other member and connected to the first said member, said glides permitting a pull of a sufficient amount to overcome the friction applied and a sliding of both units, each along the member to which it is slidably connected, with an elongation of the flexible connection between said elements and a diminishing of the overlapping relation of the flexible members.

NATHANIEL N. OKUN.
